WRINGER

Sidney S. Holland, Gard F. Traughber, and Reuben J. McVey, Sandusky, Ohio, assignors, by mesne assignments, to The Apex Electrical Manufacturing Company, Cleveland, Ohio, a corporation of Ohio

Original application February 16, 1934, Serial No. 711,558. Patent No. 2,048,741, dated July 28, 1936. Divided and this application December 16, 1935, Serial No. 54,680

4 Claims. (Cl. 68—32)

This invention relates to washing machines, and more particularly to those of the swinging wringer type, the present invention being a division of our co-pending application, Serial No. 5 711,558, filed February 16, 1934, which has matured into Patent No. 2,048,741.

A washing machine of the type to which our invention relates usually includes an agitator located within the tub element of the machine for 10 agitating wash water within the tub and a wringer mounted on the tub adapted for operation in any of several positions to permit wringing of the cleansed articles from the wash water to a rinsing tub and from the rinsing tub back to the wash 15 tub, or to a basket, both the agitator and wringer being driven from a single motor mounted on the tub base.

The principal object of the present invention is to provide a washing machine of this character 20 constructed in a manner to avert tendency of the tub to tip under weight of the wringer when it is swung to the positions as above noted.

In accomplishing these and other objects of the invention as hereinafter pointed out, we have provided improved details of structure, the preferred forms of which are illustrated in the accompanying drawings, wherein:

Fig. 1 is a perspective view of a washing machine and its wringer embodying the features of 30 our invention.

Fig. 2 is a horizontal section on the line 2—2 of Fig. 1, the wringer being shown in dotted lines to better illustrate the relative positions of the motor, transmission mechanism, and wringer 35 whereby a substantially balanced construction is provided to avert tendency of tipping of the machine under weight of the wringer.

Fig. 3 is an enlarged, vertical section through the offset portion of the wringer driving mechanism and support.

Fig. 4 is a horizontal section on the line 4—4 of Fig. 3.

Fig. 5 is a horizontal section on the line 5—5 of Fig. 3.

45 Referring more in detail to the drawings:

1 designates the tub of a domestic washing machine that is mounted on a base 2 comprising a bed ring 3 supported by spaced legs 4, preferably arranged in diametric pairs and provided with 50 caster wheels 5. The tub 1 contains an agitator of dolly or other well-known type (not shown) adapted for actuation by a shaft 6 suitably extended through the bottom of the tub and connected with a main driving shaft 7 suitably connected with a motor 8. Mounted adjacent the

bottom of the tub, laterally of one of the legs 6 and preferably on the bed ring 3, is a gear housing 9 containing a worm gear 10 (Fig. 2), that is operable from a worm 11 on the main driving shaft 7. Operable from the worm gear, by a cam 12 or other suitable means, is a pitman 13 having a transmission connection 14 for oscillating the agitator shaft 6 when the motor is energized.

Extending from the top of the gear housing 9 is a vertical, tubular housing 15 encasing a driving 10 shaft 16 which has driving connection with the worm wheel 10 to rotate synchronously with the agitator. Mounted on the top of the tubular housing 15 and spaced below the rim of the tub is an elbow housing 17 preferably of split construction to permit access to a universal joint indicated at 18 (Fig. 3).

The universal joint 18 includes a stub shaft 19 journaled in a bearing 20 that is mounted in the horizontal arm of the elbow housing, the shaft 20 19 having a stop collar 21 on its power end and having a reduced extension 22 at its opposite end projecting beyond the end of the bearing 20, on which a pinion 23 is fixed, preferably by a pin 24. Mounted on the bearing 20 by means of a collar 25 and attached to the side of the tub 1 by a boss 26 and by a boss 27 extending from the elbow housing 17, is a gear housing 28 including a body portion 29 enclosing the driving pinion 23 and bevelled gears presently described, the terminals 30 and 31 of the housing being of the particular construction for adapting the housing to the purposes of our invention. The gear housing is attached to the elbow housing by cap screws 32 projecting through ears 33 in the elbow housing 35 and into threaded sockets in the ears 34 on the gear housing.

Extending centrally through the gear housing 28 is a vertical shaft 35 having its lower end longitudinally movable in a socket 36 in the lower 40 housing terminal 30 and its upper end slidably projected through a bearing aperture 37 in the cover plate 38 at the top of the upper terminal of the gear housing and into a chamber 39 formed by an upstanding, annular flange 40 on, and integral with the cover plate 38. Mounted on the shaft 35, preferably by pins 41, are bevelled gears 42 and 43 adapted for selective engagement with the pinion 23 to effect rotation of the transmission shaft in either direction in response to constant rotation of the shaft 16.

Selective engagement of the gears 42 and 43 with the pinion 23 is preferably effected by fixing the gears on the shaft by the pins 41, previously mentioned, and longitudinal shift of the 55

transmission shaft through a cam mechanism including pins 44 extending radially from a collar 45 on the shaft 35 above the upper bevelled gear and retained in engagement therewith by a 5 thrust washer 46 that is fixed to the shaft by a pin 47. The pins 44 may consist of cylindrical studs having shanks 48 threaded into sockets 49 in the collar 45, and extended through vertical slots 50 in a cylindrical extension 51 of the body 10 28. Rotatably mounted in an annular seat 52 countersunk in the outer face of the extension 51 is a split collar 53 having inclined, slightly arcuate cam grooves 54 in its inner face (Fig. 8), into which the outer ends of the respective pins 15 44 are projected, the pins 44 being preferably provided with rollers 55 to afford anti-friction bearing of the pins on the edges of the vertical slots 50 and on inclined, slightly arcuate edges of the cam grooves 54, thereby facilitating shifting action of the shaft 35.

The split portions of the collar are secured about the extension 51 by a stud bolt 57 projecting through ears 58 on the collars, and having a nut 59 threaded on the end thereof.

25 The collar 53 is provided with handles 60 located about the collar so that one of them is always accessible to the operator of the washing machine standing in any of the customary positions relatively thereto. The collar is retained 30 in any of its selected positions by a spring-pressed ball 61 slidably mounted in a bore 62 in the collar and engageable in one of a series of sockets 63 formed in the periphery of the sleeve 51.

35 The gear housing 28, and its associated parts just described, are located in substantially vertical alignment with the leg 4 from which the transmission gear housing 9 and tubular housing 15 are offset, as clearly shown in Fig. 1, to rotatably mount the wringer in offset relation at the opposite side of the leg, as now to be described.

40 Mounted on and rotatable about an annular flange 40 and in an arcuate groove 64 in the top of the cover plate 38, for support therein, and 45 preferably resting on the top edge of the annular flange, is the shank 65 of an upper elbow housing 66 constituting a direct support for the wringer mechanism, the shank being readily removable from and replaceable on the upper terminal of the gear housing when the wringer is to 50 be separated from the machine for shipment, storage or repairs and readily replaced on the terminal for reassembly with the machine.

55 Slidably extending through and rotatably mounted in the bearing 67 at the upper end of the shank 65 is the stub shaft 68 of an upper universal joint, the stub shaft 68 having a coupling pin 69 projected diametrically from its lower end to removably seat a jaw 70 located 60 within the chamber 39 and formed on a collar 71 keyed to the upper end of the transmission shaft 35 by a pin 72. The upper end of the jaw 70 preferably terminates below the top of the flange 40 so that the jaw may be completely 65 housed when the upper elbow housing 66 is in place.

The stub shaft 68 is provided at its upper end with a yoke member 73, including a collar 74 constituting a stop or keeper and adapted for 70 flexible connection with a similar collar 75 of a stub shaft 76 rotatable in a bearing 77 within the upper horizontal portion of the elbow housing 66, the outer end of the stub shaft terminating within a chamber 78 in the end of the elbow 75 housing and provided with a coupling pin 79

adapted to engage the coupling collar of one of the roller shafts 82 of wringer mechanism 83 mounted on a flange 84 of the elbow housing 66, preferably by means of cap screws 85.

In assembling the wringer mechanism with its 5 elbow housing the coupling jaw on the wringer shaft is moved over the coupling pin on the universal stub shaft 76 to establish the driving connection, and when the wringer mechanism is to be mounted on the tub, the elbow housing with 10 the wringer mechanism on it is set over the annular flange on the transmission housing, the coupling pin on the universal joint finding its seat in the jaw 70 of the transmission shaft to 15 establish driving connection.

It is apparent that with the construction described the wringer roller shaft may be rotated in either direction when the wringer is in any position it may assume about the extended axis of the shaft 35. In order to retain the wringer 20 mechanism in any of its several positions at which it may be most conveniently located for receiving articles from the washing tub for delivery into a rinsing tub, from the rinsing tub either back to the washing tub, or to a basket, or 25 at a neutral position at which it is out of the way of the operator, I provide a latch for holding the wringer mechanism in either operating position or in neutral position.

The latch mechanism referred to preferably 30 consists of a pin 101 slidably mounted in the base flange 102 at the bottom of the upper elbow housing 66, and in a protuberance 103 on the base ring, the upper end of the latch being slidably guided in a socket 104 in a protuberance 105 35 on the side of the upper elbow housing and the lower end of the latch pin being adapted for projection into one of a plurality of sockets 106 formed in the cover plate 38 according to the position of the wringer. The pin 101 is operable 40 by a finger piece 108 fixed thereto and cooperative with a thumb hold 110 on the protuberance 105 so that the latch handle or thumb hold may be grasped with one hand while the operator employs the other to turn the wringer to adjusted 45 position.

Assuming the driving mechanism to be constructed and assembled with the tub, the tub base and wringer as described, and with the wringer arranged to take articles from the washing tub for delivery into a rinsing tub that may be located adjacent the washing tub (Fig. 1), the transmission gearing is set with the bevelled gear 43 in mesh with the driving pinion 23 so that the connected wringer roller is rotated forwardly relative to the washing tub and articles passed through the wringer will be delivered to the adjacent rinsing tub. When, however, the wringer is to be operated in a reverse direction, the collar 53 is rotated about the sleeve 51 on the gear housing 28, whereupon the transmission shaft is shifted downwardly, thereby disconnecting the lower bevel gear 43 from the driving pinion and meshing the upper gear therewith.

In the above operation, rotation of the collar 85 53 moves the cam track 54 over the pins 44 on the collar 45 to lower the transmission shaft, the vertical slots 46 in the sleeve 41 restricting movement of the pins to a vertical plane in response to movement of the inclined cam track 54 over 70 the pins. Upon initial movement of the collar 53 for shifting the transmission shaft, the ball latch 61 is moved out of its socket 63 in the sleeve 51 against the tension of its spring and held in its extended position by contact with 75

the wall of the sleeve until the collar has been rotated to the next adjacent position, whereupon the ball is forced into a corresponding socket to hold the collar in place; it being apparent that the gears may be retained at either limit of their movement to effect rotation of the wringer in either direction, or in a neutral position at which the wringer is inoperative because of disengagement of both bevelled gears from the driving pinion.

The wringer mechanism is released for positioning in a different location by lifting the latch pin from the socket in which it is seated at that time, and retained in its location by automatic repositioning of the latch pin in a socket corresponding to the new position. When the wringer is in position to receive and deliver the articles desired, power is transmitted from the motor to actuate the drive shaft, the worm and worm wheel, the lower universal joint, the transmission shaft, the upper universal joint, and the wringer, regardless of position of the wringer and in either forward or reverse direction, according to selected engagement of the bevel gears on the transmission shaft with the driving pinion on the lower universal joint.

When the wringer is in the position illustrated in Fig. 1 the weight thereof is substantially offset by the transmission and driving means at the opposite side of the leg. As the wringer is swung from the position illustrated in Fig. 1 and toward a radial position relatively to the tub, the wringer is counterbalanced by the tub and driving mechanism supported thereunder. As the wringer 35 swings across to the opposite side of the leg the tipping moment exerted by the wringer is lessened so that there is no tendency for the tub to tip in that direction. The forces resulting from swinging of the wringer outwardly from the tub are transmitted downwardly in substantial alignment with the leg, and the leg serves as a brace to prevent tipping of the machine. As the position of the wringer is changed and its moment increased, the relative moment of the tub and base is thus increased to stabilize the machine.

What we claim and desire to secure by Letters Patent is:

1. In combination with a washing machine having a tub supported by spaced legs and having a wringer, driving mechanism for the wringer including a vertical shaft offset laterally at a side of one of the legs, a housing for the shaft and having a lateral extension projecting over and above the leg, a housing connected with said lateral extension, a driven shaft supported by the last named housing in vertical alignment with the leg, a driving connection in said lateral extension for interconnecting said shafts, driving means connected with the lower end of the vertical shaft, means supporting the wringer for

swinging movement about the axis of the driven shaft, and a driving connection connecting the driven shaft with the wringer.

2. In combination with a washing machine having a tub supported by spaced legs and having a wringer, driving mechanism for the wringer including a vertical shaft offset laterally at a side of one of the legs, a housing for the shaft and having a lateral extension directed toward the leg, a housing connected with said lateral extension and spaced above the leg, a driven shaft supported by the last named housing in vertical alignment with the leg, a driving connection in said lateral extension for interconnecting said shafts, means connecting the driven shaft with the wringer, driving means connected with the lower end of the vertical shaft, means supporting the wringer for swinging movement on the last named housing whereby said wringer is adapted to swing about an axis directly above said leg in 20 said last named housing, and means for reversing rotation of the driven shaft.

3. In combination with a washing machine having a tub supported by spaced legs and having a wringer, driving mechanism for the wringer including a vertical shaft offset laterally at a side of one of the legs, a housing for the shaft and having a lateral extension projecting over the leg, a gear housing connected with said lateral extension, a driven shaft supported by the gear housing in alignment with said leg, gearing in said gear housing, driving connections between the gears and said shafts, driving means connected with the lower end of the vertical shaft, means supporting the wringer for swinging movement 35 on the gear housing about the axis of the driven shaft, and means for connecting the driven shaft with the wringer.

4. In combination with a washing machine having a tub supported by spaced legs and having a wringer, driving mechanism for the wringer offset laterally at a side of one of the legs, a transmission housing above said leg, a transmission gearing in the transmission housing, a driving connection between the driving mechanism and the transmission gearing, a housing for the driving connection including a portion extending above said driving mechanism and terminating in a lateral arm connected with the transmission housing for enclosing said driving connection, an elbow-shaped member rotatable on the transmission housing and having an arm portion carrying said wringer, and a driving connection enclosed in the elbow-shaped member for operating the wringer from said transmission gearing.
